TAPE PULLING DEVICE

August D. Eitzen, Rockville Centre, N. Y., assignor to News Projection Corporation, New York, N. Y., a corporation of New York

Application August 20, 1929, Serial No. 387,104
Renewed May 17, 1933

16 Claims. (Cl. 271—2.4)

This invention relates to stock quotation projecting machines in general and more especially to an improved electrical device for controlling the movement of the tape.

5 Among the objects of the present invention it is aimed to provide an improved electrical device cooperating with a tension device in engagement with the stock quotation tape for controlling the motor of the tape pulling means.

10 It is still another object of the present invention to provide an improved electrical device for the motor of a tape pulling device, which electrical device is operable to control the amount of current of the motor correspondingly to advance the tape.

15 It is still another object of the present invention to provide an improved electrical device and an improved spark quenching device for such electrical device for the motor of the tape pulling device of a stock quotation projecting machine, which electrical device is operable to control the amount of current passing to the motor and to change the amount of current passing to the motor.

20 These and other features, capabilities and advantages of the invention will appear from the subjoined detail description of one embodiment thereof, illustrated in the accompanying drawing in which:

25 Figure 1 is a side elevation diagrammatically showing a stock quotation projecting machine equipped with the present improved electrical device;

30 Fig. 2 is a plan view diagrammatically shown of a stock quotation projecting machine equipped with the present improvement;

35 Fig. 3 is a section on the line 3—3 of Fig. 2; and

40 Fig. 4 is an end elevation of the device shown in Fig. 3 partly broken away.

In the embodiment shown, the ticker tape T issues from the ticker in the upper portion of the housing 1 and cooperates with a device responsive to deflections in the tape. In the present instance, it passes under the roller 2 to the light aperture formed above the extension 3 of the projector 4. From the extension 3, the tape T passes down under the idler 5 and then up above the tape pulling roller 6, then again down under the idler 7 and then over and onto the rewind reel 8.

The tape pulling roller, as shown in my co-pending application, Serial No. 343,363, filed Feb. 28, 1929, Patent No. 1,910,154, is provided with a worm wheel 9 fixedly connected to the tape pull-

ing roller 6 and in mesh with the worm 10 on the shaft 11. The shaft 11 is provided with a pulley 12 at its outer end which is connected by the belt 13 with the pulley 14 of the motor 15. The shaft of the worm wheel 9 is also provided with a pulley 16 which is connected to the pulley 17 fixedly connected to the reel 8 by means of the spring belt 18.

The roller 2 is preferably provided with two lateral guiding flanges 19 and 20 and two annular cutaway portions 21 and 22 of the roller 2 are provided to clear the two rows of printed matter formed on the tape to protect such printed matter from smearing. The roller 2 is pivotally mounted at the end of the arm 23 which is fixedly mounted on the shaft 24 journaled in the wall member 25 of the housing 26.

The shaft 24 is preferably provided with two bearings 27 and 28 which are disposed within the housing 26 and spaced from one another to receive the arm 23 fixedly mounted on said shaft 24. The outer end of the arm 23 is preferably bifurcated, as shown, to receive the upper end of the link 30 and pivotally connect the same by means of the pin 31. The lower end of the link 30 is provided with a pin which extends through the bifurcated portions of the upper end of the plunger 32 to pivotally connect the link 30 to the upper end of the plunger 32. The lower end of the plunger or well 32 is adapted to travel up and down in the chamber 33 formed by the bracket 34. The lower end of the chamber 33 is provided with a lateral opening 35 to communicate with the central chamber 36 of the wire supporting member 37. The central chamber 36, as clearly appears from Fig. 3, inclines upwardly from the chamber 33 and terminates at its upper end in the vertical extension 38, extending upwardly from the central chamber 36 which is preferably provided with an oil cup 39.

The upper end of the plunger 32 is preferably provided with a skirt 40 which extends down around the outside of the upper end of the bracket 34 surrounding the chamber 33. The bracket 34, wire support 37 and link 30 are preferably composed of some insulating material such as bakelite. The wire support 37 is preferably provided with a plurality of contacts 41, 42, 43, 44, 45 and 46 which communicate at their inner ends with the central chamber 36. The contact 41 is preferably connected with the contact bar 47 by the conductor 48, which contact bar 47 is connected by the conductor 49 to the main outlet. The other lead of the main outlet 50 is connected by the contact bar 51 to the contact conductor 52 which

is connected to the contact 53 formed in the bracket 34 and communicating at its lower end with the lateral opening 35 of the bracket 34. The contact 41 is connected with the contact 42 by 5 the resistance coil 54. The contact 42 is connected to the contact 43 by the resistance coil 55. The contact 43 is connected to the contact 44 by the resistance coil 56. The contact 44 is connected to the contact 45 by the resistance coil 10 57. The contact 45 is connected to the contact 46 by the resistance coil 58.

The chamber 33 is preferably filled with a conductive liquid, such as mercury which will cover the contact point 53 in the lateral outlet 15 35 when the plunger 32 is disposed in the raised position shown in Fig. 3. The area of the central opening 36 so corresponds to the form and size of the plunger 32 relative to the chamber 33 that the mercury located in the chamber 33 will be 20 gradually displaced by the plunger 32 as the same descends to cause the mercury gradually to rise in the central passage 36 until it finally makes contact with the contact 41 at the lowest position of the plunger 32.

From the foregoing it will be apparent that when the plunger 32 is in its lowermost position and consequently the mercury at its highest level, the contact will be made direct by means of the conductor 55, contact 41, mercury M, contact 53 25 and conductor 52 with the main leads 49 and 50; that when the plunger 32 is in its next lowest position where the mercury clears the contact 41 but engages the contact 42, the resistance coil 54 will be cut in to reduce the amperage; 30 and in turn, as the plunger 32 rises and the level of the mercury M descends, more and more resistance will be cut in gradually to decrease the amperage to a comparative minimum when all of the resistance coils 54 to 58 are cut in. At this 35 time, the flow of current will of course be so reduced that the motor 15 which is connected in series with the main leads 49 and 50 by means of the conductors 59 and 60 is operating at its lowest speed. Preferably, in the present instance, a small amount of oil O is carried by the mercury so as to promptly quench any spark that is formed when the mercury makes or breaks contact with one of the contacts 41 to 45 inclusive.

It is of course obvious that the plunger 32 will remain in its highest position when the slack in the tape T has been taken up by the take-up roller 61 as is the case when the ticker has ceased operating for a short period, and that during the 50 operation of the ticker, a loop is always formed of greater or less degree adjacent to the roller 2 gradually to cut out more and more resistance to speed up the motor 15 in turn to cause the slack in the tape T to be taken up at a greater 55 or less speed depending upon the speed of the ticker. When the ticker has ceased to operate and the slack in the tape T has been taken up in turn to raise the plunger to its highest position where the level of the mercury M is not high enough to engage the contact 46, the current will of course at this point be interrupted and cause the motor 15 to come to rest and in turn to cause the take-up roller 6 to come to rest.

The cup 39, in the present instance, has a 60 small oil reservoir to insure providing the necessary coating or covering of oil on the mercury end.

The skirt 40 serves mainly as a dust cap to protect the well or chamber 33 from dust and the 65 like.

It will also be apparent from the foregoing that the diameter of the plunger 32 relative to the diameter of the well 33 is such that the small amount of clearance between the two will retard the movement of the plunger up or down due to 5 the fact that the mercury being displaced must be squeezed up in this narrow clearance between the plunger 32 and well 33, and thereby acting as a dash-pot or dampening device. As a result of the foregoing, the whip of the tape so 10 objectionable when the tape engaging roller 2 is free to drop with the formation of a loop, resulting in objectionable vibrations being formed in the tape which will be many times magnified during projection, cannot occur. Furthermore 15 with the electric make and break devices of this character heretofore in use, the tape did not start moving from a position of rest until the ticker had ejected such tape to form a considerable loop, the loop required to permit the contact 20 arm finally to make contact, resulting in a succession of blows on the tape by the tape engaging roller 2 before contact was made to cause the motor for the tape puller finally to get started. With the present invention, however, on the 25 other hand, the tape engaging roller 2 gradually follows the loop being formed without being permitted to strike it due to the dampening effect aforesaid and on the other hand almost simultaneously, causes contact to be made to form a 30 slow gradual start to the advancing movement of the tape. And in turn, when the ticker comes to rest, instead of permitting the tape pulling motor to continue at top speed until the contact is broken to effect the sudden arrest of the 35 tape at the light aperture, with the present invention, the successive increasing resistances will be cut in gradually to slow down the tape to the condition of rest. The value of this slow start and stop of the tape is especially apparent 40 with the high speed tickers installed within the last few years by means of which quotations are today being printed at the rate of about five hundred characters per minute and which machines are reputed to be capable of being speeded up to 45 nine hundred characters per minute, when consideration is taken of the eye strain necessarily resulting to the observer of the projected quotations from a sudden start or sudden stop of the tape at this speed.

It is obvious that various changes and modifications may be made to the details of description without departing from the general spirit of the invention as set forth in the appended claims.

I claim:

1. The combination with a stock ticker tape, of a tape pulling device for drawing the tape across the light aperture of a projector, a device for controlling the speed of operation of said tape 60 pulling device according to the rate at which the tape is supplied to the light aperture consisting of a rheostat having a plurality of contacts, a mercury bath, a straight plunger operatively mounted adjacent to said rheostat in a vertically 65 extending path of movement for causing said mercury to cut in the successive resistances of said rheostat to facilitate a gradual start from a period of rest and a gradual arrest of the tape, and means sensitive to the slack in the tape 70 at the entrance to the light aperture operatively connected to said plunger to actuate said plunger.

2. The combination with a stock ticker tape, of a tape puller for pulling the tape across the light aperture of a projecting machine as it is 75

- delivered thereto, a tape feed for feeding the tape to the light aperture, the tape puller and tape feed cooperating to form slack at the entrance to the light aperture when the tape feed 5 operates and to take up the slack so formed when the tape feed comes to rest, an electric motor operatively connected for driving said tape puller, a rheostat for controlling the speed of operation of the motor and consequently of the tape puller, a mercury bath, a vertically extending straight plunger for causing the mercury in said bath to cut in the successive resistances of said rheostat as the plunger rises to facilitate a gradual start 10 from a period of rest and a gradual arrest of the tape, and an arm resting on the tape at the entrance to said light aperture and operatively connected to said plunger to actuate the same in a vertically extending path of movement adjacent to said rheostat.
- 20 3. The combination with a stock ticker tape, of a tape feed, a tape puller for pulling the tape across the light aperture of a projecting machine as it is delivered by the tape feed, the tape puller and tape feed cooperating to form slack 15 at the entrance to the light aperture when the tape feed operates and to take up the slack so formed when the tape feed comes to rest, an electric motor operatively connected for driving said tape puller, a rheostat for controlling the speed 20 of operation of the motor and consequently of the tape puller, there being an upwardly inclined chamber, the successive contacts of the rheostat communicating with said chamber, a mercury bath, a substantially straight plunger operatively 25 mounted adjacent to said rheostat in a vertically extending path of movement to cause the mercury in said bath to move upwardly into said chamber to cut out the successive resistances of the rheostat as the mercury rises and consequently as the plunger descends to facilitate a gradual start from 30 a period of rest and a gradual arrest of the tape, and an arm resting on the tape at the entrance end to said light aperture and operatively connected to said plunger to cause said plunger to descend when slack is formed in said tape.
4. The combination with a stock ticker tape, of a tape feed, a tape puller for pulling the tape through the projecting machine as it is delivered by the tape feed, the tape puller and tape feed 35 cooperating to form slack at the entrance end to the light aperture when the tape feed operates and to take up the slack so formed when the tape feed comes to rest, an electric motor operatively connected for driving said tape puller, a rheostat for controlling the speed of operation of the motor and consequently of the tape puller, there being an upwardly inclined chamber, the successive contacts of the rheostat communicating with said chamber, a mercury bath, a substantially 40 straight plunger operatively mounted adjacent to said rheostat in a vertically extending path of movement to cause the mercury in said bath to move upwardly into said chamber to cut out the successive resistances of the rheostat as the mercury rises and consequently as the plunger descends to facilitate a gradual start from a period 45 of rest and a gradual arrest of the tape, an arm resting on the tape at the entrance end to said light aperture and operatively connected to said plunger to cause said plunger to descend when slack is formed in said tape, and a supply of oil on the surface of the mercury in said bath to promptly quench the formation of any sparks when contact is made or broken with said rheostat.
5. The combination with a stock ticker tape, of a tape feed, a tape puller for pulling the tape across the light aperture of a projecting machine as it is delivered by the tape feed, the tape puller and tape feed cooperating to form slack 5 at the entrance end to said light aperture when the tape feed operates and to take up the slack so formed when the tape feed comes to rest, an electric motor operatively connected for driving said tape puller, a mercury rheostat for controlling the speed of operation of said motor consisting of an insulated bracket having a vertically extending well, an inclined chamber extending upwardly from the lower end of said well, contacts at the opposite ends of said inclined chamber 10 electrically connected with the electric motor, a plurality of contacts intermediate said end contacts disposed to extend into said chamber, a plurality of resistance coils connecting the successive contacts, mercury disposed in said well, a plunger slidably mounted in said well operative to force the mercury into said chamber to cut out successive resistances by contact with successive contacts to facilitate a gradual start from a period of rest and a gradual arrest of the tape, 15 and an arm resting on the tape at the entrance end to said light aperture and operatively connected with said plunger to cause said mercury to rise when slack is formed in said tape and said plunger descends.
6. The combination with a stock ticker tape, of a tape feed, a tape puller for pulling the tape across the light aperture of a projecting machine as it is delivered by the tape feed, the tape puller and tape feed cooperating to form slack 20 at the entrance end to said light aperture when the tape feed operates and to take up the slack so formed when the tape feed comes to rest, an electric motor operatively connected for driving said tape puller, a mercury rheostat for controlling the speed of operation of said motor consisting of an insulated bracket having a vertically extending well, an inclined chamber extending upwardly from the lower end of said well, contacts at the opposite ends of said inclined chamber 25 electrically connected with the electric motor, a plurality of contacts intermediate said end contacts disposed to extend into said chamber, a plurality of resistance coils connecting the successive contacts, mercury disposed in said well, a plunger slidably mounted in said well operative to force the mercury into said chamber to cut out successive resistances by contact with successive contacts, and an arm resting 30 on the tape at the entrance end to said light aperture and operatively connected with said plunger to cause said mercury to rise when slack is formed in said tape and said plunger descends, the clearance between said plunger and the side walls of said well being comparatively slight and the mercury being forced through said clearance as the plunger rises or falls to retard or cushion the movement of said plunger and consequently to prevent the sudden movement of said arm resulting in the possible jerk or jar to the tape 35 especially when starting from a period of rest or when returning to a period of rest.
7. The combination with a stock ticker tape, of a tape feed, a tape puller for pulling the tape across the light aperture of a projecting machine as it is delivered by the tape feed, the tape puller and tape feed cooperating to form slack 40 at the entrance end to said light aperture when the tape feed operates and to take up the slack so formed when the tape feed comes to rest, an 45

- electric motor operatively connected for driving said tape puller, a mercury rheostat for controlling the speed of operation of said motor consisting of an insulated bracket having a vertically extending well, an inclined chamber extending upwardly from the lower end of said well, contacts at the opposite ends of said inclined chamber electrically connected with the electric motor, a plurality of contacts intermediate said end contacts disposed to extend into said chamber, a plurality of resistance coils connecting the successive contacts, mercury disposed in said well, a plunger slidably mounted in said well operative to force the mercury into said chamber to cut out successive resistances by contact with successive contacts, an arm resting on the tape at the entrance end to said light aperture and operatively connected with said plunger to cause said mercury to rise when slack is formed in said tape and said plunger descends, the clearance between said plunger and the side walls of said well being comparatively slight and the mercury being forced through said clearance as the plunger rises or falls to retard or cushion the movement of said plunger and consequently to prevent the sudden movement of said arm resulting in the possible jerk or jar to the tape especially when starting from a period of rest or when returning to a period of rest, and an oil supply located in said mercury to promptly quench the formation of any sparks when making or breaking contact between the mercury and the contacts of said rheostat.
8. The combination with a stock ticker tape, of a tape pulling device for drawing the tape across the light aperture of a projector, a device for controlling the operation of said tape pulling device according to the rate at which the tape is supplied to the light aperture consisting of a rheostat having a plurality of contacts, a well of conductive liquid, a substantially straight plunger adjacent to said rheostat, said well having one vertically extending passage for receiving said plunger, and a second passage extending laterally from said vertically extending passage in communication with said contacts, and means responsive to deflections in the tape to actuate said plunger in turn to raise the level of said conductive liquid and thereby cut in the successive resistances of said rheostat according to the magnitude of the deflection in the tape.
9. The combination with a stock ticker tape, of a tape pulling device for drawing the tape across the light aperture of a projector, a device for controlling the speed of operation of said tape pulling device according to the rate at which the tape is supplied to the light aperture consisting of a rheostat having a plurality of contacts, a well having a supply of conductive liquid, a plunger vertically movable in said well adjacent to said rheostat to cause said conductive liquid to rise and cut in the successive resistances of said rheostat, and means responsive to deflections in the tape operatively connected to said plunger to actuate said plunger.
10. The combination with a stock ticker tape, of a tape pulling device for drawing the tape across the light aperture of a projector, a device for controlling the operation of said tape pulling device according to the rate at which the tape is supplied to the light aperture consisting of a rheostat having a plurality of contacts, a well containing a supply of conductive liquid, a lever responsive to deflections in the tape, a link, and a plunger vertically movable in said well adjacent to said rheostat and operatively connected by said

link to said lever to change the level of said conductive liquid in turn to cut in the successive resistances of said rheostat according to the magnitude of the deflection in the tape.

11. The combination with a stock ticker tape, of a tape pulling device for drawing the tape across the light aperture of a projector, a device for controlling the operation of said tape pulling device according to the rate at which the tape is supplied to the light aperture consisting of a rheostat having a plurality of contacts, a well containing a supply of conductive liquid, a lever responsive to deflections in the tape, an arm fixed to rock with said lever, a link pivotally connected to said arm, and a plunger vertically movable in said well adjacent to said rheostat pivotally connected to said link to change the level of said conductive liquid in turn to cut in successive resistances of said rheostat according to the magnitude of the deflection in the tape.

12. The combination with a stock ticker tape, of a tape pulling device for drawing the tape across the light aperture of a projector, a device for controlling the operation of said tape pulling device according to the rate at which the tape is supplied to the light aperture consisting of a rheostat having a plurality of contacts, a vertically movable plunger adjacent to said rheostat, a lever responsive to deflections in the tape, a link operatively connecting said plunger to said lever, and means operatively connecting said plunger to said contacts to cut in the successive resistances of the rheostat according to the magnitude of the deflection in the tape.

13. The combination with a stock ticker tape, of a tape pulling device for drawing the tape across the light aperture of a projector, a device for controlling the operation of said tape pulling device according to the rate at which the tape is supplied to the light aperture consisting of a rheostat having a plurality of contacts, a vertically movable plunger adjacent to said rheostat, a lever resting on the tape and responsive to deflections in the tape, an arm fixed to rock with said lever, a link operatively connecting said arm with said plunger, and means operatively connecting said plunger to said contacts to cut in the successive resistances of the rheostat according to the magnitude of the deflection in the tape.

14. The combination with a stock ticker tape, of a tape feed, a tape puller for pulling the tape across the light aperture of a projecting machine as it is delivered by the tape feed, the tape puller and tape feed cooperating to form slack at the entrance end to said light aperture when the tape feed operates and to take up the slack so formed when the tape feed comes to rest, an electric motor operatively connected for driving said tape puller, a mercury rheostat for controlling the speed of operation of said motor consisting of an insulated bracket having a vertically extending well, a chamber extending upwardly from the lower end of said well, contacts at the opposite ends of said chamber electrically connected with the electric motor, a plurality of contacts intermediate said end contacts disposed to extend into said chamber, a plurality of resistance coils connecting the successive contacts, mercury disposed in said well, a plunger slidably mounted in said well operative to force the mercury into said chamber to cut out successive resistances by contact with successive contacts to facilitate a gradual start from a period of rest and a gradual arrest of the tape, and an arm resting on the tape at the entrance end to said light aperture.

and operatively connected with said plunger to cause said mercury to rise when slack is formed in said tape and said plunger descends.

15. The combination with a stock ticker tape, 5 of a tape feed, a tape puller for pulling the tape across the light aperture of a projecting machine as it is delivered by the tape feed, the tape puller and tape feed cooperating to form slack at the entrance end to said light aperture when the tape feed operates and to take up the slack so formed when the tape feed comes to rest, an electric motor operatively connected for driving said tape puller, a mercury rheostat for controlling the speed of operation of said motor consisting of an 10 insulated bracket having a vertically extending well, a chamber extending upwardly from the lower end of said well, contacts at the opposite ends of said chamber electrically connected with the electric motor, a plurality of contacts intermediate said end contacts disposed to extend into said chamber, a plurality of resistance coils connecting the successive contacts, mercury disposed in said well, a plunger slidably mounted in said well operative to force the mercury into said 15 chamber to cut out successive resistances by contact with successive contacts, an arm resting on the tape at the entrance end to said light aperture and operatively connected with said plunger to cause said mercury to rise when slack is formed 20 in said tape and said plunger descends, the clearance between said plunger and the side walls of said well being comparatively slight and the mercury being forced through said clearance as the plunger rises or falls to retard or cushion the 25 movement of said plunger and consequently to prevent the sudden movement of said arm resulting in the possible jerk or jar to the tape especially when starting from a period of rest or when returning to a period of rest.

- 30 40 16. The combination with a stock ticker tape,

of a tape feed, a tape puller for pulling the tape across the light aperture of a projecting machine as it is delivered by the tape feed, the tape puller and tape feed cooperating to form slack at the entrance end to said light aperture when the tape 5 feed operates and to take up the slack so formed when the tape feed comes to rest, an electric motor operatively connected for driving said tape puller, a mercury rheostat for controlling the speed of operation of said motor consisting of an 10 insulated bracket having a vertically extending well, a chamber extending upwardly from the lower end of said well, contacts at the opposite ends of said chamber electrically connected with the electric motor, a plurality of contacts intermediate 15 said end contacts disposed to extend into said chamber, a plurality of resistance coils connecting the successive contacts, mercury disposed in said well, a plunger slidably mounted in said well operative to force the mercury into said 20 chamber to cut out successive resistances by contact with successive contacts, an arm resting on the tape at the entrance end to said light aperture and operatively connected with said plunger to cause said mercury to rise when slack is formed 25 in said tape and said plunger descends, the clearance between said plunger and the side walls of said well being comparatively slight and the mercury being forced through said clearance as the plunger rises or falls to retard or cushion the 30 movement of said plunger and consequently to prevent the sudden movement of said arm resulting in the possible jerk or jar to the tape especially when starting from a period of rest or when returning to a period of rest, and an oil supply 35 located in said mercury to promptly quench the formation of any sparks when making or breaking contact between the mercury and the contacts of said rheostat.

AUGUST D. EITZEN. 40
